UNITED STATES PATENT OFFICE.

FRANKLIN A. STEARN, OF ORANGE, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

Application filed December 4, 1926. Serial No. 152,594.

This invention relates to telephone exchange systems in which connections are established by means of automatic switching apparatus operated under control of central office register senders.

According to the present invention a number of decoding devices are provided in common to a number of senders, with means for associating simultaneously a plurality of said devices with respective senders for decoding registrations established in said senders, and for thereupon setting the switch controlling registers of such senders in accordance with the decoded registrations.

According to another aspect of the invention, means is provided to repeatedly set a selection controlling register in accordance with different portions of the recorded wanted number. According to an additional aspect of the invention, a designation may be rendered ineffective and another designation set up when a call is attempted by a subscriber whose service is restricted.

Briefly, the operation of the system is as follows: The initiation of a call causes the association of an idle sender with the first or district selector. The series of impulses corresponding to the office code are first registered, whereupon the decoder is connected with the sender. The decoder then deciphers the registered office code, designates a single point or relay individual to the route to be employed in reaching the wanted office and operates the selection controlling register of the sender. At the same time, the number of the wanted substation is recorded. When the trunk to the wanted office has been selected under the control of the selection register, this register is released and is reset in accordance with the recorded substation number. If the wanted office is a machine switching office, this register now controls the switches at that office to select the wanted line, whereas if the wanted office is a manual office, the dial register controls the transmission of code impulses to set the relay call indicator at that office.

A clearer understanding of the invention will be obtained from a consideration of the following description in connection with the appended claims and attached drawings in which,

Figs. 1 and 2 show the relationship between senders and decoders with a decoder connector in more detail;

Fig. 3 shows a calling substation, a district selector circuit in detail, and a diagrammatic showing of the train of switches for connecting the district selector with a called substation;

Figs. 4 and 5 show the control apparatus of the sender, Fig. 4 including a schematic showing of a link circuit;

Fig. 6 shows the counting relays which control the selections;

Figs. 7, 8 and 9 show the recording or dial register of the sender;

Fig. 10 shows the selection register of the sender;

Figs. 11 and 12 show the decoder connector;

Fig. 13 shows the incoming register of the decoder;

Figs. 14 and 15 show the outgoing register of the decoder;

Figs. 16, 17 and 18 show the deciphering apparatus;

Fig. 19 shows the manner in which Figs. 3 to 18 should be arranged; and

Fig. 20 shows the manner in which Figs. 1 and 2 should be arranged.

Detailed description.

Referring first to Figs. 3 to 18, let it be assumed that the subscriber at substation 301 wishes to converse with the subscriber at station 302 whose line terminates in a machine switching office and whose number is Falmouth 6780. The district selector shown is of the type disclosed in United States Patent 1,589,402 to O. H. Kopp, granted June 22, 1926. This type of district selector is associated with an idle sender by means of a link circuit and normally stands associated with a link and with its sequence switch in position 2. Reference is made to the above mentioned patent for the operation of the link circuit and that of the district selector in advancing to position 2.

The removal of the receiver at substation 301 causes certain operations described in the said Kopp patent to take place, which result in the connection of ground to conductor 303 through the link circuit 490. This completes a circuit extending from conductor 303 over the upper contacts of cam 304, winding of relay 305 to battery. Relay 305 operates and closes a circuit from ground over the lower left contact of cam 306, right front contact of relay 305, upper left contact of cam 307, to conductor 308 and the link circuit,

100

105

110

which causes the link circuit to start hunting for an idle sender. Relay 305 also closes a circuit from battery through the winding of line finder up-drive magnet 309, outer left 5 front contact of relay 305, lower left contact of cam 310, right front contact of relay 305, to ground at the lower left contact of cam 306. The line finder is moved upward under the control of magnet 309 in search of the calling 10 line which is identified by battery connected to terminal 319. As soon as the line finder starts upward, a locking circuit is closed for relay 305, over the inner left front contact, upper left contact of cam 311, back contact of relay 312, commutator strip 313, brush 314 to ground. The link circuit in starting its operation also connects ground to conductor 315, completing a circuit over the upper left contact of cam 316, upper left contact of cam 317, left winding of relay 318 to battery. Relay 318 operates and locks over its outer left front contact, lower right and upper left contacts of cam 345 to ground. When the line finder brushes encounter the terminals 25 of the calling line, battery connected to terminal 319 completes a circuit through the winding of relay 312, upper contacts of cam 320 to ground at the lower contact of cam 321. Relay 312 operates in this circuit, shunting 30 its winding by resistance 365 and opening the locking circuit of relay 305. The release of relay 305 opens the circuit of up-drive magnet 309, bringing the line finder to rest on the terminals of the calling line. With relay 305 35 released and relay 318 operated, a circuit is closed from battery through the winding of sequence switch magnet 300, lower right contact of cam 327, right front contact of relay 318, inner right back contact of relay 305, to ground at the lower left contact of relay 306, advancing sequence switch 300 to position 3, wherupon relay 318 is released. With sequence switch 300 in positions 3 to 18, inclusive, battery is connected through resistance 322 over the lower left contact of cam 323, lower back contact of relay 324, resistance 325, to terminal 326 to mark the calling line busy as long as it is engaged by the line finder brushes. 40 In the meantime, the sender selector of link 490 has been hunting an idle sender. An idle sender is characterized by battery through 150 ohms resistances connected to its test conductor 401, the circuit for which may be traced over the back contact of relay 402, back contact of relay 403, back contact of relay 404, resistance 405 to battery. When the sender selector encounters this battery, the link circuit is operated to connect sender control conductor 406 of the sender through to conductor 428 of the district selector. When sequence switch 300 reaches position 3, therefore, a circuit is closed from battery through the lower winding of relay 324, upper right contact of cam 330, conductor 328, through the link cir-

cuit to conductor 406, right back contact of relay 407, inner right back contact of relay 408, conductor 409, through the middle and right windings of relay 501 to ground. Relay 324 is marginal and does not operate at this time. 70 Relay 501 operates, closing an obvious circuit for relay 502. Relay 502, in operating, closes a circuit from ground over its left front contact, upper right contact of cam 410, left winding of relay 411 to battery. Relay 75 411 operates and closes an obvious circuit for sequence magnet 400, advancing the sequence switch to position 2. Relays 411 and 445 may now be operated under the control of interrupters 447, and 449 to advance sequence 80 switch 400, thus serving to time the various functions of the sender and to cause alarms and signals to be operated, if these functions do not take place in the allotted length of time. These operations will be described in 85 detail later. Relay 502 also closes a circuit from ground at its left front contact, to the winding of relay 413, resistance 412 and battery, operating relay 413 which closes the holding circuit for itself at its outermost 90 contact and grounds conductor 414, which is also grounded over the upper left contact of cam 415 by the advance of sequence switch 400 to position 2. The connection of ground to conductor 414 completes a circuit for relay 403, which in turn operates relay 462 and 95 relay 404. Relay 403 also disconnects battery from contact 401 to prevent the selection of this sender by another link circuit. This also serves to cause the link circuit to connect the pulsing conductors, the fundamental circuit conductors and the sender control conductor through from the district selector directly to the sender. That is, it connects conductors 328, 315, 331, 308 and 100 303 through to conductors 406, 416, 417, 419 and 418, respectively.

Registration of called number.

The dialing circuit may now be traced 110 from battery through the left winding of relay 420, inner left back contact of relay 421, conductor 417, through the link circuit to conductor 331, lower left contact of cam 366, lowermost contact of relay 324, terminal 333, 115 over the subscriber's line back to terminal 334, upper back contact of relay 324, left contact of cam 366, conductor 331, through the link circuit to conductor 416, outer left back contact of relay 421, resistance 422, outer 120 left back contact of relay 407 to ground. The pulsing relay 420 operates in this circuit closing a circuit from ground at the inner left back contact of relay 423, front contact of relay 420, winding of relay 424, to battery. Relay 424, in turn, closes an obvious circuit for relay 425 and relay 425 closes one for relay 426. Relays 425 and 426 are slow-to-release and hence are not released during short interruptions of the circuit of relay 125 130

420. When sequence switch 400 advanced to position 2, a circuit was closed from battery, through the winding of relay 727, back contact of relay 726, to grounded conductor 414. 5 Therefore relay 426 in operating, closes a circuit from ground through the secondary winding of tone coil 463, right winding of relay 420, conductor 728, uppermost front contact of relay 727, conductor 464, inner 10 left front contact of relay 426, to ground. The tone from primary coil 463 is induced in the right winding of relay 420 and thence over the dialing circuit to the receiver, notifying the calling subscriber that the sender 15 is right to receive dial impulses.

According to the assumption made above that the called subscriber's number is Falmouth 6780, the calling subscriber will now operate his dial to send out three series of 20 impulses of 3, 2 and 5 pulses each, representing the office code, and of 6, 7, 8 and 10 each, representing the numerical designation. As the dial returns to normal following the first 25 operation it will open the circuit of relay 420 three times. Relay 420 releases at each interruption and opens the circuit of relay 424 which also releases. The release of relay 424 opens the circuit of relay 425 but that relay, being slow to release, remains operated 30 between pulses. With relay 424 released a circuit is closed from battery through the winding of relay 427, inner right back contact of relay 424, outer front contact of relay 426 to ground, relay 426 being held operated by its slow-to-release character, as 35 well as the slow-release character of relay 425. Relay 427 is also slow to release so that it does not retract its armature during the short operated periods of relay 424 during 40 dialing but does close its back contact between digits.

At the first release of relay 420 a circuit is closed from ground over the back contacts of relays 423 and 420, left front contact of 45 relay 425 to conductor 428 and thence over the upper back contacts of relays 710, 708, 706, 704, and 702, to the winding of relay 701 and battery. Relay 701 operates and closes a locking circuit for itself through 50 the winding of relay 702, front contact of relay 701, upper back contact of relay 704, conductor 713 to ground over the outer right back contact of relay 424 and the outer front contact of relay 426, or over the front contact of relay 427 and the inner front contact of relay 426. This alternative arrangement insures the closure of the locking circuit for the register relays, the circuit over the contact of relay 424 being ready before relay 427 55 has time to operate, and the circuit over the front contact of relay 427 remaining closed throughout each digit. Relay 702 does not operate in the above traced locking circuit until the reoperation of relay 420, following 60 the first pulse, opens the energizing circuit 65

of relay 701 and removes the shunt around the winding of relay 702. As soon as relay 702 operates, a circuit is closed from ground over its lower front contact, conductor 752, next to the inner front contact of relay 727, 70 upper winding of relay 722 to battery.

The next interruption of the circuit of relay 420 by the dial connects ground to conductor 428, over the back contacts of relays 710, 708, 706 and 704, front contact of relay 702 75 to the winding of relay 703 and battery. As in the case of relay 701, relay 703 closes a locking circuit through the winding of relay 704 extending over the front contact of relay 703 and the back contact of relay 708 to 80 grounded conductor 713. At the close of the pulse relay 704 operates, opening the locking circuit of relays 701 and 702, thus in turn opening the circuit of relay 722. It also connects ground over its lower front contact to 85 conductor 753 completing a circuit over the middle front contact of relay 727, upper winding of relay 723 to battery. At the next impulse the release of relay 420 completes a circuit from ground over its back contact as 90 before traced to conductor 428, back contacts of relays 710, 708 and 706, front contact of relay 704, winding of relay 705 to battery. Relay 705 closes the usual locking circuit for itself through the winding of relay 706 to 95 grounded conductor 713 over the back contact of relay 708. At the end of the pulse, relay 706 operates, but since the locking circuit of relays 703 and 704 extends over the back contact of relay 708, these relays also 100 remain operated and ground remains connected to conductor 753 and is connected now to conductor 752. In consequence, relays 722 and 723 are both operated at this time.

Since there are only three impulses in this 105 series, relay 420 now remains operated for a sufficient length of time to permit relay 427 to release. The release of relay 427 completes a circuit from ground over the inner front contact of relay 426, back contact of relay 110 427, conductor 429, over a chain circuit including the back contacts of relays 937, 927, 917, 837, 827, 817 and 737, lower winding of relay 726, lower front contact and winding of relay 723 to battery and also over the lower 115 front contacts of relay 723, lower front contact and winding of relay 722 to battery. Relay 726 operates and closes a locking circuit for itself from battery through its upper winding and lower front contact to grounded conductor 414. The operation of relay 726 also closes a direct locking ground for relays 722 and 723 independent of the chain circuit. A circuit is also closed from battery through the winding of relay 737, back contact of relay 120 736, lower front contact of relay 726 to grounded conductor 414, operating relay 737 to extend conductors 751 to 755 to the relays of register 730. The operation of relay 726 125 opens the circuit of relay 727, disconnecting 130

register 720 from the operating conductors 751 to 755 and opening the dial tone circuit.

It will be noted that the holding circuit for relay 722 extends through the front contact 5 of relay 723 and also over the front contact of relay 725. This is due to the fact that the digit 1 is never employed as the first digit of an office code since it may be simulated by accident. Therefore, the relay 722 is not held 10 operated except in combination with other relays. If relay 722 is operated alone in response to a false pulse the energizing circuit of relay 726 is not completed at the release of relay 427, and when the relays of register 15 700 are released as described below the circuit returns to the condition before the pulse was received.

During the interval between digits relay 424 remains operated. Therefore, the release 20 of relay 427 disconnects ground from conductor 713 releasing the operated counting relays of primary register 700. It will be noted that the contacts of relay 427 are so arranged that ground is not disconnected 25 from conductor 713 until after the circuit of relay 726 is completed so that the relays of register 700 are not released until after the relays of register 720 are locked up.

When the subscriber operates his dial to 30 send the second digit, it will open the circuit of relay 420 twice, operating relays 701, 702, 703 and 704 in the manner described for the first digit. Relay 733 will be operated, in the same manner as relay 723 was. The release of relay 427 at the end of the digit 35 causes the operation of relay 736 in a circuit similar to the circuit of relay 726, except that the back contact of relay 737 is not included. Relay 736 in operating closes ground from conductor 414 over its lower front contacts, and the lower front contact and lower winding of relay 733 to battery holding that relay 40 operated. The operation of relay 736 completes a circuit for relay 817, after which the relays of register 700 and relay 737 are 45 released, and the circuit prepared for receiving the third digit.

The first three impulses of the third digit, 5, are received as previously described. In 50 response to the fourth impulse, relay 707 is operated and closes a locking circuit for itself through the winding of relay 708 over back contact of relay 710 to conductor 713. When relay 708 operates at the completion of 55 the pulse, relays 703, 704, 705 and 706 are all released, removing ground from conductors 752 and 753. Relay 708 connects ground to conductor 754, operating relay 814. The 60 fifth interruption of the circuit completes a circuit for relay 709, which in turn closes a locking circuit for itself through the winding of relay 710, over the back contact of relay 704, to conductor 713. Relay 710, when it operates, opens the locking circuit of relays 65 707 and 708 releasing relay 814 which was

operated by them and connects ground over its lower front contact, lower back contact of relay 712, to conductor 755, uppermost front contact of relay 817 to the upper winding of relay 815 and battery. Relay 710 in 70 operating also closes a circuit from battery through the winding of relay 711, back contact of relay 712, upper front contact of relay 710 to grounded conductor 713. Relay 711 closes a locking circuit for itself through 75 the winding of relay 712 which is ineffective as long as relay 710 remains operated. Following the last impulse relay 427 is released as above described, relay 816 is operated and locks over conductor 430 to ground at the 80 lower contact of cam 415 in the same manner as did relay 726, holding relay 815 operated and extending a circuit for operating relay 827.

The operation of relay 816 indicates that 85 the office code has been completely registered. A circuit is thereupon completed from grounded conductor 414 over the lower front contact of relay 736, upper front contact of relay 816, conductor 818, winding of relay 90 431, to battery. Relay 481, in turn, closes a circuit from battery through resistance 432, left back contact of relay 433, back contact of relay 434, left front contact of relay 431, back contact of relay 435, conductor 436, upper winding of relay 1201, back contact of relay 1202, to ground. Relay 1201 operates in this circuit to initiate the association of an idle decoder with the sender, which operation 95 will be described hereinafter.

When the subscriber dials the fourth digit, 6, the relays of register 700 are operated in the same manner as was described for the first five impulses. The 6th impulse will cause the completion of a circuit from ground 105 to conductor 428 over the front contact of relay 710 and the back contact of relays 706, 704 and 702 to the winding of relay 701 which operates in the same manner as before. The locking circuit of relays 709 and 710 is maintained at this time so that upon the operation of relay 702 at the close of the last impulse 110 ground remains connected to conductors 752 and 755 causing the continued operation of relays 825 and 822 in register 820. As before, the release of relay 427 causes the operation of relay 826, the release of register 700 and relay 827 and the operation of relay 827 to render register 830 effective to receive the 115 next digit.

When the subscriber dials the next digit, 7, the register 700 operates in the manner described for the first 6 impulses. The 7th impulse causes the completion of the circuit of relay 703 over the front contact of relay 710, back contacts of relays 706 and 704 and front contact of relay 702. The locking circuit of relay 703 is the same as on its first operation. At the end of the pulse, relay 704 operates 125 opening the locking circuit of relays 701, 702, 130

709 and 710. It also connects ground to conductor 753. The release of relay 710 permits relay 712 to operate in the locking circuit of relay 711 and the operation of relay 712 connects ground over the back contact of relay 710 and the inner front contact of relay 712 to conductor 755 so that relays 833 and 835 are operated at the end of the last impulse. As before, the release of relay 427 causes the 10 operation of relay 836, the release of register 700 and relay 837 and the operation of relay 917.

In response to the dialing of the next digit, 8, the register 700 is operated as described 15 for the first seven impulses and the circuit for operating relay 705 in response to the 8th digit is the same as first traced. The locking circuit is also the same as previously described. The locking circuit of relays 711 and 712 is independent of any of the other 20 relays and therefore these relays remain operated until the register is released. It will be remembered that the operation of relay 706 does not release relays 703 and 704. Therefore, at this time conductors 752, 753, 25 and 755 are grounded, causing the operation of relays 912, 913, and 915. The release of relay 427 following the last impulse causes the operation of relay 916 holding relays 912, 30 913 and 915 operated, releasing register 700 and relay 917 and operating relay 927.

In response to the last digit 0 the register 700 records the first 8 impulses in the manner described. The 9th pulse is recorded on relays 707 and 708 and the 10th pulse causes the operation of relays 709 and 710. With 35 relays 709, 710, 711, and 712 operated, a circuit is closed from ground over the front contact of relay 710, lower front contact of relay 712 to conductor 751 and thence over the lowermost front contact of relay 927 to the winding of relay 921. The operation of relay 710 disconnects ground from conductor 755 and releases relay 925 which has been operated since the reception of the 5th impulse. The release of relay 427 causes the operation 40 of relay 926, release of register 700 and the operation of relay 937. Since no station's digit is dialed, the operation of relay 937 is ineffective. Following the registration of the units digit, primary register 700 releases as before. The called number has now been recorded resulting in the operation of relays 722 and 723 of register 720, relay 733 of register 730, relay 815 of register 810, relays 822 and 825 of register 820, relays 832 and 835 of register 830, relays 912, 913 and 915 of register 910, and relay 921 of register 920.

60 Connection with decoder.

In the meantime the decoder connector has been operating to decipher the register setting. Relay 1201 operates in the circuit traced for it over the front contact of relay 65 421, and closes a locking circuit for itself

from battery on conductor 436 through its lower winding and lower front contact to ground through the winding of relay 1202. Relay 1202 in operating, opens the energizing circuit of relay 1201 and also that of the 70 other relays such as relay 1223 individual to other senders in the decoder connector. It also closes a circuit from ground over its upper front contact, front contact of relay 1201 to the winding of relays 1203 and 1101 75 in parallel. These relays are each provided with a plurality of armatures, the contacts of which are each multiplied through similar relays individual to other senders and to the decoders. Relay 1202 likewise closes a decoder start circuit from battery over its lower front contact, back contacts of relays 1204 and 1205 and the remaining decoder relays to insure that the channel is idle, over the upper back contact of relay 1206, winding of 80 relay 1207 to ground at the back contact of relay 1208. Relay 1207 operates and closes a locking circuit for itself from battery over the front contact of relay 1202, lower winding and lower front contact of relay 1207 to 85 ground through the winding of relay 1208. Relay 1208 operates and closes a circuit from ground over its front contact, upper front contact of relay 1207 to the winding of decoder relays 1205 and 1152 in parallel. The 90 operation in these relays extends the control conductors from the sender through to the decoder. With relay 1205 operated, a circuit is closed from battery through the upper winding of relay 1206, contact 1210 of make-busy jack 1211, front contact of relay 1205, to ground on grid wire 1209. These circuits will be discussed in greater detail later in connection with Figs. 1 and 2.

95 Operation of decoder.

100 As soon as multi-contact relays 1205 and 1152 operate the following circuits are completed from the recording register of the sender to the incoming registers of the decoder. From grounded conductor 414, over the lower front contacts of relay 726, lower back contact of relay 725, conductor 714, through the decoder connector to conductor 1103, winding of relays 1305 and 1307 in series to 110 battery; from grounded connector 414, over the lower front contacts of relay 726, over the lower front contact of relay 723, conductor 716, through the decoder connector to conductor 1105, windings of relays 1302 and 1304 115 to battery; from grounded conductor 414 over the lower front contacts of relay 726, lower front contacts of relay 723, lower front contact of relay 722, conductor 715, through the decoder connector, conductor 1104, winding 120 of relay 1301 to battery; from grounded contact 414, over the lower front contacts of relay 736, lower back contact of relay 735, conductor 717, through the decoder connector, conductor 1106, through the windings of relays 125 130

1315 and 1317 to battery; from grounded conductor 414 over the lower front contacts of relay 736, lower front contact of relay 733, conductor 718, through the decoder connector, conductor 1107, through the windings of relays 1312 and 1314 to battery; from grounded conductor 430, over the lower front contacts of relay 816, lower front contact of relay 815, conductor 819, through the decoder connector, conductor 1108, windings of relays 1326 and 1328 to battery. Because of the completion of these circuits, relays 1301, 1302, 1304, 1305, 1307, 1312, 1314, 1315, 1317, 1326, 1328 are simultaneously operated.

15 As soon as registers 1310, 1320 and 1300 have been operated a circuit will be completed from ground over the outer right contact of relay 1307, outer right contact of relay 1317, outer right contact of relay 1328 to the winding of relay 1330. The operation of relay 1330 completes three circuits over the contacts of registers 1300, 1310 and 1320 for designating a point for the extension of a call to the wanted office. A circuit may first be traced from ground over the right front contact of relay 1330, back contact of relay 1311, front contact of relay 1312, outer right front contact of relay 1315, to the windings of relays 1601, 1602 and 1603 in parallel. A second circuit extends from ground over the inner left front contact of relay 1330, back contact of relays 1321, 1322, and 1323, inner right front contact of relay 1328, conductor 1329, which extends over the middle contact of relay 1603, to conductor 1604, and grid wire 1704 which acts as a front contact to multi-contact relays 1700, 1701, etc. A third circuit extends from ground over the outer left front contact of relay 1320, back contact of relay 1331, front contact of relays 1301, 1304, and 1305 to conductor 1309 and the winding of relay 1701. With relay 1701 operated, grid wire 1704 is connected over conductor 1705 to terminal 1831 on cross connecting rack 1830.

45 This point is cross connected over rack 1832 to relay 1800 which is individual to the proper routing for the Falmouth office. There is a relay, such as relay 1800, for each routing and as many relays as are necessary for all offices reached directly from the office shown. If certain subscribers are restricted from calling some offices in the exchange area, they will be served by district selectors and senders which supply a ground connection to the decoder connector for the purpose of operating relays, such as relays 1334 and 1335 whereby the routing set up by the office designation will be changed to one of a special nature so that the call may be properly supervised.

60 The operation of relay 1800, assuming that the cross connections are those shown, will establish a plurality of circuits for setting the outgoing decoder registers in accordance with the routing desired. These circuits may be traced as follows: from ground over the inner contact of relay 1800, cross connecting racks 1810 and 1811, conductor 1820, right winding of relay 1505, to battery; second contact of relay 1800, conductor 1821, right winding of relay 1517 to battery; third contact of relay 1800, conductor 1823, right winding of relay 1533 to battery; fourth contact of relay 1800, cross connecting racks 1810 and 1812, conductor 1825, right winding of relay 1447 to battery; fifth contact of relay 1800, conductor 1824, right winding of relay 1423 to battery; outer contact of relay 1800, conductor 1822, right winding of relay 1408 to battery. Relay 1447 in operating closes an obvious circuit for relay 1451, relay 1408 closes an obvious circuit for relay 1411 and relay 1517 closes an obvious circuit for relay 1512. Therefore, the operation of relay 1800 will cause the operation of relays 1447, 1451, 1423, 1408, 1411, 1533, 1512, 1517 and 1505. It will be noted that those relays operated directly from the routing relays 1800 are provided with two windings over either one of which they may be operated. When operated through their left windings, they close auxiliary circuits for purposes which will be explained later.

65 The operated relays connect ground to certain of the conductors leading to the sender and from there to the selection controlling register in Fig. 10. These circuits are completed simultaneously and may be traced as follows: from ground over the inner right contact of relay 1505, conductor 1506, through the decoder connector to conductor 1215, winding of relay 503 to battery; from ground over the outer right front contact of relay 1517, conductor 1522, through the decoder connector to conductor 1216, winding of relay 1071 to battery; from ground over the outer right front contact of relay 1512, conductor 1523, to conductor 1217, winding of the relay 1062 to battery; from ground at the outer right contact of relay 1533, conductor 1543, to conductor 1219, winding of relay 1042 to battery; from ground over the inner right contact of relay 1411, conductor 1412, to conductor 1110, winding of relay 1034 to battery; from ground over the middle right contact of relay 1411, conductor 1413, to conductor 1111, winding of relay 1032, to battery; from ground over the outer right contact of relay 1423, conductor 1427, to conductor 1112, winding of relay 1022 to battery; from ground at the outer right contact of relay 1447, conductor 1454, to conductor 1114, winding of relay 1013, to battery; from ground over the middle right contact of relay 1451, conductor 1456, to conductor 1116, winding of relay 1012 to battery; from ground over the inner right front contact of relay 1451, conductor 1455, to conductor 1115, winding of relay 1011, to battery. Therefore, in the selection control register, class 130

relay 503 will be operated, district brush relay 1062, talking selection relay 1071, office brush relay 1042, district group relays 1032 and 1034, office group relay 1022 and compensating resistance relays 1011, 1012 and 1013. Upon the operation of the outgoing register relays of the decoder, a series circuit is completed from ground over the outer right front contact of relay 1505, inner right front contact of relay 1512, inner right front contact of relay 1533, outer right front contact of relay 1411, inner right front contact of relay 1423, outer right front contact of relay 1451, winding of relay 1332, to battery.

5 Relay 1332 is a slow-to-operate relay so that it does not close its front contact until ample time has elapsed to permit the operation of the relays of the selection controlling register. When relay 1332 closes its front contact, it 10 completes a circuit from ground to conductor 1333, through the decoder connector to conductor 1220 and thence through the winding of relay 435 to battery. Relay 435 operates and closes a locking circuit for itself 15 over its inner right front contact to conductor 818, front contact of relay 816, lower front contact of relay 736 to grounded conductor 414. It also supplies locking ground for the selection controlling register relays 20 over a circuit which may be traced from ground at the right contact of cam 415, middle right contact of relay 435, conductor 438, to cam 504. From thence it extends directly to the locking armatures of the talking selection 25 relays, the stations delay relays and the compensating resistance relays. From cam 504, locking circuits extend over the lower left contact of cam 504, conductor 506, to the district brush register relays and the district 30 group relays; over the right contact of cam 504, to conductor 505, and the locking armatures of the office brush relays and the office group relays; over the upper contact of cam 504, to the locking contacts of the class relays.

35 The operation of relay 435, also disconnects battery from conductor 436, releasing relay 1201, and in turn, relay 1202 and the remaining control relays of the decoder connector. The disconnection of the decoder releases all 40 the relays of the decoder. The operation of relay 435, likewise, completes the fundamental circuit for controlling district brush selection.

Timing switch.

45 Before describing the operation of selecting the wanted office, the functioning of sequence switch 400 will be described. As above indicated, this sequence switch serves 50 to time the functioning of the sender. The advance of the sequence switch from position 1 to position 2 has been described. The circuits are so arranged that relay 445 is operated in positions 2+3, 5+6, and 15+17, under the control of interrupter 447, and in

positions 8+11, under the control of interrupter 449. The operation of relay 445 closes a circuit from battery through its winding, and the winding of relay 411 over the front contact of relay 445 to ground at 70 the upper right contact of cam 448. The operation of relay 411 advances sequence switch 400, but as the sequence switch passes from position 2 to 3, etc., the circuit of relay 411 is opened and the advance to the next position depends on the operation of relay 445 by the interrupter. The circuit is also arranged to operate relay 411 directly through its left winding at the completion of certain operations to advance sequence switch 400 75 independent of the interrupter. When the first digit has been dialed, register 720 set and relay 726 operated, a circuit is closed from grounded conductor 414 over the upper front contact of relay 726, upper right contact of cam 439 to the right winding of relay 411. The operation of relay 411 advances sequence switch 400 to position 5.

80 When a complete number has been dialed, a circuit is closed from battery through the left winding of relay 411, left contact of cam 439, conductor 440, over the upper front contact of relay 916, conductor 441, to ground at the upper contact of cam 442. Relay 411 operates in this circuit and advances sequence switch 400 to position 8. If a short number is dialed such as an operator's code, class relay 507 is operated, and the circuit of relay 411 is extended from conductor 440, inner 85 back contact of relay 508, to ground at the outer right front contact of relay 507. Relay 411 is next operated over circuits which depend upon the type of call and whether or not, a station's digit is to be expected. In the case of a full mechanical call such as is being 90 traced, no station's digit is used and relay 411 is immediately operated in a circuit extending from battery through left winding of relay 411, lower right contact of cam 410, conductors 448 and 738 and the back contacts 95 of relays 1051 and 1053 to ground. The operation in the case of calls to manual offices will be described later. Relay 411 is next operated over the upper left contact of cam 410, back contact of relays 413 and 407, when the 100 sender has released.

105 If there is a delay in dialing or the completion of the registration, these circuits through the left winding of relay 411 may not be closed at the proper time. If sequence 110 switch 400 reaches position 4, for example, under the control of the interrupter, a circuit will be closed from battery through the right winding of relay 453, left contact of cam 452 to ground at the back contact of relay 411. 115 Relay 453 locks to grounded conductor 414 and closes a circuit for operating relay 481 and associating a decoder with the sender. In addition, it connects ground over its inner 120 right front contact to conductor 454, which 125

is extended through the decoder connector to conductor 1119 and relay 1331. Relay 1331 disconnects ground from register 1300 preventing the completion of the circuits necessary to select a routing and instead closes a circuit from ground over its front contact to conductor 1338, which extends to terminal 1833 on cross-connecting rack 1826 from whence it is cross-connected to the windings 10 of a relay similar to relay 1800, but which designates a routing which causes the extension of the call to the operator's position. If, however, the first digit is dialed properly, but the dialing is not completed in the proper 15 time, sequence switch 400 will arrive in position 7 under the control of the interrupter, but will not be able to move out of that position. A circuit will be thereupon closed from ground over the upper contact of cam 450, 20 left back contact of relay 411 and relay 421 to lamp 451 which is located at a monitor's position.

If the sender does not release in the length 25 of time, sequence switch 400 will remain in position 18 and a circuit will be closed from ground through interrupter 449, lower contact of cam 450, left back contact of relay 411, outer right back contact of relay 421, to lamp 451, causing that lamp to flash indicating to 30 the monitoring operator that the sender has failed to release.

Selections.

Assuming that registration has taken place 35 in a normal manner, the operation of relay 435 above described, establishes the fundamental circuit for district brush selection. This circuit may be traced from battery through the left winding of relay 318, upper 40 left contact of cam 317, lower right contact of cam 316, conductor 303, through the link circuit to conductor 418, front contact of relay 435, conductor 458, upper contact of cam 510, winding of stepping relay 511, back 45 contact of relay 620, outer back contact of relay 623, through the right winding of relay 512 which is shunted by resistance 530 and the upper contact of cam 531, resistance 513, to ground at the lower right contact of cam 50 553. Relays 318 and 511 operate in this circuit but the current does not flow in the right direction to operate relay 512.

Relay 318 in operating closes a holding 55 circuit for itself through its left winding and outer left front contact, lower left contact of cam 317, lower right contact of cam 316 to the fundamental circuit as traced. It also closes a circuit from battery, through the winding of sequence switch magnet 300, 60 lower right contact of cam 327, right front contact of relay 318, inner back contact of relay 305, to ground at the lower left contact of cam 306. Sequence switch 300 advances to position 4 in this circuit, opening the 65 energizing circuit of relay 318, but main-

taining the holding circuit. In position 4, a circuit is closed from battery through the winding of updrive magnet 336, lower contacts of cam 330, right front contact of relay 318, to ground as traced. Upon the operation 70 of magnet 336, the district selector is moved upward in a brush selecting operation. As the shaft moves upward, brush 337 makes contact with commutator strip 338, intermittently closing a circuit from ground at 75 the lower contact of cam 321, brush 337, conducting segments of strip 338, right contacts of cam 316, to the fundamental circuit as traced. This circuit holds relay 318 operated but causes the release of relay 511. 80

When relay 511 first operated, it closed a counting relay circuit, which may be traced from ground, over the upper contact of cam 514, front contact of relay 511, lower right and upper left contacts of cam 515, to conductor 85 554, and thence over the lower left contact of cam 516, conductor 517, to the outer back contact of relays 1064, and 1063, inner front contact of relay 1062, to conductor 1080, back contact of the No. 1' counting relay 618, winding of the No. 1 counting relay 617, conductor 624, to battery at the contact of cam 459. Relay 617 operates and closes a locking circuit for itself through the winding of relay 618, front contact of relay 617, 90 inner back contact of relay 623 to ground at the right contact of cam 518. Relay 618 does not operate in this circuit, being shunted by the energizing circuit of relay 617. When 95 relay 511 is shunted and released by the first conducting segment of commutator strip 338, relay 618 operates, extending the counting relay circuit over its front contact, conductors 1084 and 625, lower contact of cam 519, conductor 520, to the winding of the No. 0 relay 105 619 and battery. When brush 337 encounters the insulating segment of strip 338, relay 511 reoperates, in turn, operating relay 619. Relay 619 locks through the windings of relays 620 and 621 in parallel, over the front contact 110 of relay 619 to ground at the back contact of relay 622. As before, relays 620 and 621 do not operate until relay 511 is released by the second conducting segment of strip 338.

When this occurs relay 620 opens the fundamental circuit, releasing relay 318. Relay 318 opens the circuit of updrive magnet 336 and brings the selector to rest in position to trip the proper set of brushes. It also closes a circuit through the winding of sequence switch magnet 300, right contacts of cam 339, back contact of relay 318, to ground as traced, advancing sequence switch 300 to position 5. When sequence switch 300 reaches position 5, a circuit is closed from battery through the winding of tripping magnet 367, lower right and upper left contacts of cam 311, back contact of relay 311 (which released when switch 300 left position 3), commutator strip 313, brush 314, to 125 130

ground. The operation of relay 367 prepares for tripping the selected brush set at the beginning of group selection.

Relay 621 in operating, closes a circuit from ground over the front contact of relay 621, right back contact of relay 521, uppermost contact of cam 527, winding of relay 623 to battery. Relay 623 locks over its inner contact to ground at the right contact of relay 518 opening the locking circuit of relays 617 and 618. It also extends a circuit from battery through winding of relay 622 over its inner contacts to this same ground. Relay 622 in operating, opens the locking circuit of relays 619, 620 and 621, releasing them. When relay 621 closes its back contact, a circuit is completed from ground, over the back contact of cam 621, outer front contact of relay 623, upper right contact of cam 623, winding of sequence switch magnet 500 to battery. Sequence switch 500 advances to position 2 in this circuit opening the locking circuit of relay 623 and the energizing circuit of relay 622.

With sequence switch 500 in position 2, the fundamental circuit is reestablished as previously traced to conductor 418, then extends over the right contact of cam 510 to the winding of relay 511 and is further completed as previously described. Relay 318 locks, advancing sequence switch 300 to position 5 and causing the operation of magnet 336 in the manner described in position 3. In position 5, however, the intermittent shunting circuit for relay 511 extends from conductor 303 over the lower left contact of cam 316, lower right contact of relay 317, to commutator strip 341, brush 340 and ground at the lower contact of cam 321. Relay 511 in operating, establishes a counting relay circuit, extending as before traced, to conductor 554, over the upper contact of cam 516, conductor 524, back contact of relay 1031, outer front contact of relay 1032, conductor 1083, back contact of No. 2' relay 616, winding of relay 45 No. 2 counting relay 615 to battery over conductor 624. Relay 615 operates and locks through the winding of relay 616, in the usual manner. The first revertive impulse causes the operation of the No. 2' relay 616 and the second revertive impulse causes the No. 1' relay 618 to operate in the locking circuit of the No. 1 relay extending the energizing circuit over its front contact to conductors 1084 and 625, right contact of cam 519, conductor 525, front contact of relay 1084, conductor 1082, back contact of the No. 9' counting relay 602, winding of the No. 9 relay 601 to battery. The next five impulses cause the successive operation of relays 602, 604, 606, 608 and 610 in the manner previously described. Relay 610 in operating extends the circuit to the winding of relay 619, so that the following impulse causes the operation 65 of relays 621 and 620 to open the fundamental

circuit, operate relays 622 and 623, release the counting relays and advance sequence switch 500 to position 3.

The release of relay 318 due to the opening of the fundamental circuit, brings the district selector to rest on the first trunk of the desired group. The release of relay 318 advances sequence switch 300 to position 7 over the previously traced circuit over its back contact. In position 7 relay 318 is reoperated in a circuit through its right winding, and the lower right contact of cam 342, upper left contact of cam 311, back contact of relay 312 to ground over commutator strip 313. Relay 318 closes a locking circuit for itself over its outer left front contact, left contacts of cam 345, to sleeve brush 346 which is completed, provided the outgoing trunk is busy, to ground, when the sequence switch reaches position $7\frac{1}{2}$. The operation of relay 318 closes the previously traced circuit over its front contact for advancing sequence switch 300 to position 8. If the trunk is busy, relay 318 is maintained operated in position 8 and operates updrive magnet 336 to cause the selector to hunt for an idle outgoing trunk. When an idle trunk is found, relay 318 releases the updrive magnet and advancing the sequence switch to position 9. However, relay 318 does not release until the brushes 95 are properly centered, due to a holding circuit extending from ground to the right armature and front contact of relay 318 as previously traced, over the lower right and upper left contacts of cam 320, brush 344, centering strip 343, right contacts of cam 342, to the right winding of relay 318 and battery. As soon as relay 318 releases, ground is connected to brush 346, over the right contacts of cam 345, left back contact of relay 318, 100 to ground at the upper right contact of cam 321 to hold the outgoing trunk busy. As soon as sequence switch 300 reaches position $8\frac{3}{4}$ ground is connected to the brush over the contacts of cam 345. In position 9, relay 105 329 is connected, over the upper left contact of cam 330 to conductor 328 in parallel with relay 324. Relay 329 operates and closes a circuit from battery through right winding of relay 318, lower contacts of relay 347, left 110 contact of relay 329, commutator strip 348, brush 349, to ground. The operation of relay 318 causes the advance of sequence switch 300 to position 10 in which position subsequent 115 selections take place and relay 318 remains 120 operated under the control of relay 329.

With sequence switch 300 in position 10 and sequence switch 500 in position 3, the trunk outgoing to the office selector is tested. This test consists of the establishment of a 125 metallic circuit extending from the office selector over the upper right and lower left contacts of cam 351, right back contact of relay 352, to conductor 303, through the link circuit to conductor 418, lower contact of cam 130

526, resistance 527, back contact of relay 1015 in parallel with resistance 556, upper contact of cam 528, winding of relay 529, back contact of relay 620, outer back contact of relay 623, shunted right winding of relay 512, lower right contact of cam 531, front contact of relay 1011, resistances 1017 and 1016 in series, front contact of relay 1012, right contact of cam 532, left back contact of relay 460, conductor 419, through the link circuit to conductor 308, upper left and lower right contacts of cam 353, district selector brush 354 to the office selector. Battery and ground are supplied to the circuit from the office selector and if the trunk is normal, relay 529 will operate, in turn operating relays 533 and 534. Relay 534, in operating, closes a circuit from ground over its inner right front contact, right contact of cam 535, winding of sequence switch magnet 500 to battery, advancing sequence switch 500 to position 4.

In position 4, the fundamental circuit is reestablished, extending as traced in position 3 from the office selector 370 to conductor 418, right contact of cam 510, winding of relay 511 to the back contact of relay 620 and back to the office selector as traced in position 3. The counting relay circuit for office brush selection extends as previously traced to conductor 554, over the lower right contact of cam 516, conductor 545, back contact of relay 1041, inner right front contact of relay 1042, conductor 1081, back contact of the No. 3' relay 614, to the winding of the No. 3 counting relay 615 and battery. The office selector operates in the same manner as the district selector, sending back grounded pulses to release relay 511 and operate the counting relays. The operation of relay 618 at this time extends the counting relay circuit over the lower contact of cam 519 to the winding of relay 619, causing the office selector to come to rest in the position to select the fourth set of brushes. The operation of relays 620, 621, 622, 623 is the same as previously described, switch 500 being advanced to position 5. It is moved through position 5 by means of a circuit to ground at the lower right contact of cam 536. In advancing through position 5, the conductors connecting the office selector with the sender are discharged from any capacity charge which may exist on them by means of a metallic circuit extending from conductor 418 over the lower contact of cam 526, through resistance 527 and shunted resistance 556, left contact of cam 528, resistance 537, which is of the order of 10,000 ohms, to conductor 555. This discharge circuit or a similar one is closed as switch 500 passes through positions 9, 11, 13 and 15.

In position 6 the fundamental circuit is reestablished and a counting relay circuit closed over the contact of relay 511 to conductor 554, upper contact of cam 538, conductor 547, back contact of relay 1021, outer right

front contact of relay 1022, conductor 1083, back contact of the No. 2' relay 616 and winding of the No. 2 counting relay 615, to battery. After two revertive impulses, relay 618 is operated, and extends the counting relay circuit over the upper left contact of cam 519, conductor 548, back contact of relay 1024, conductor 520, winding of relay 619 to battery causing the selection of the 4th group. On the completion of this selection, sequence switch 500 is advanced to position 7 by relays 621 and 623.

When sequence switch 500 advanced from position 2, the locking circuit of relays 1062, 1034 and 1032 was opened and now at the advance from position 6, the locking circuit of relays 1042 and 1022 is opened. When sequence switch 500 reaches position 7, a circuit is closed from battery through the winding of relay 828, conductor 829, upper right and lower left contacts of cam 539, conductor 540, upper front contact of relay 826, lower front contact of relay 816 to grounded conductor 430. This circuit is obviously not completed until the thousands register 820 has been set. The operation of relay 828 extends the control conductors from register 820 to the windings of relays 1061 and 1064 which formerly acted as district brush register and now is repositioned to act as the incoming brush register. It will be remembered that relays 822 and 825 were operated, under the control of the dial. Therefore, two circuits were closed, one from the grounded conductor 430 over the lower front contacts of relay 826, inner lower front contact of relay 822, inner front contact of relay 828, to the winding 1061 and battery, and a second over the inner lower front contact of relay 825, upper front contact of relay 828, to the winding of relay 1064 and battery. The locking circuit of relay 623 is maintained in position 7 over the upper contact of cam 518, lower contacts of cam 461, right front contact of relay 503 to ground at the back contact of relay 828 to prevent the reestablishment of the fundamental circuit for incoming trunk test until the thousands register upon which the incoming brush selection depends, has been positioned.

With sequence switch 500 in position 7, test is made of the condition of the incoming selector and the trunk leading thereto. This is carried out by means of a circuit from battery at the incoming selector 380 to conductor 418 as previously traced, middle right front contact of relay 503, resistance 527, and shunted resistance 556, upper contact of cam 528, winding of relay 529, back contact of relay 620, outer left back contact of relay 623, shunted right winding of relay 512, left contact of cam 531, front contact of relay 1013, resistance 1017, back contact of relay 1014, left contact of cam 532, to conductor 555 and thence back to ground at the incoming selec-

tor. If the incoming selector is in normal condition and the trunk as well, relay 529 will operate, in turn operating relays 533 and 534. Relay 512 remains unoperated as before.

5 The operation of relay 534 completes a circuit from ground at its right front contact, lower left contact of cam 535, outer right front contact of relay 503, to the winding of sequence switch magnet 500, advancing it to 10 position 8.

In position 8, the fundamental circuit is reestablished, extending at this time from conductor 418, inner right front contact of relay 503, upper contact of cam 526, winding 15 of relay 511, back contact of relay 620, and thence as traced for the test circuit back to conductor 555. The counting relay circuit extends as previously traced to conductor 554, whence it extends over the right back contact 20 or relay 460, inner right back contact of relay 541, to conductor 550, over the lower left contact of cam 542, conductor 517, outer front contact of relay 1064, back contact of relay 1062, front contact of relay 1061, to conductor 25 1081, back contact of No. 3' relay 614, winding of No. 3 relay 615 to battery. Incoming brush selection takes place in the same manner as office brush selection. The operation of relays 620 and 621 following the fourth 30 retractive pulse serving to advance sequence switch 500 to position 9, releases the counting relays and advances the incoming selector to the position for making group selection. In position 9, a circuit is closed from battery 35 through the winding of relay 838, conductor 839, left contacts of cam 543, conductor 544, upper front contact of relay 836, lower front contact of relay 826, to grounded conductor 430. The operation of relay 838 extends the 40 control conductors from hundreds register 830 to the relays of the former office brush register 1050, operating relay 1042. However, incoming group selection is a function of the combined thousands and hundreds registration. It will be seen that the operation 45 of relay 838 not only extends conductors to register 1050 but also extends a circuit from conductor 441 over the front contact of relay 835, upper front contact of relay 838, to conductor 1035, winding of district group 50 relay 1031. With relay 838 operated, sequence switch 500 advances to position 10 for incoming group selection. In position 9 the circuit by which the conductors are dis- 55 charged between selections extends over the inner right front contact of relay 503 to resistance 527 instead of over the lower contact of cam 526.

The fundamental circuit is reestablished in 60 position 10 as traced for incoming brush selection and the counting relay circuit extends as traced for incoming brush selection to conductor 557, extending over the upper contact of cam 542, conductor 524, over the front contact of relay 1031, inner back contact of re-

lay 1032, to conductor 1080 and the winding of the No. 1 relay 617 causing the selection of the second incoming group. Sequence switch 500 is advanced to position 11 following this selection in the same manner as to 70 position 9. In passing through position 11, the conductors are discharged as before.

In position 12, relay 838 remains operated, holding the relays of the office brush register operated. It will be noted that the locking 75 circuits for the district and office registers were opened when sequence switch 500 left positions 2 and 6, respectively, and are not reclosed so that it is necessary to maintain relay 838 operated in order to hold register 80 1040 operated. Since relay 838 is already operated, switch 500 is immediately advanced from position 11 to position 12 over the same circuit by which it was advanced to position 10. In position 12 the fundamental circuit 85 for final brush selection is the same as in position 10. The counting relay circuit extends in this position over the lower contact of cam 514, front contact of relay 511, upper contacts of cam 515, right back contact of relay 460, inner right back contact of relay 541, conductor 550, over the lower left contact of cam 542, conductor 545, back contact of relay 1041, outer front contact of relay 1042 90 to conductor 1083 over the back contact of the No. 2' relay 616, to the winding of the No. 2 relay 615, thus causing the selection of the third final selector brush. Relays 620, 621, 622 and 623 perform their usual function of advancing the sequence switch to position 13, advancing the final selector sequence switch to make final tens selection and releasing the counting relays. 95

When sequence switch 500 leaves position 12 relay 838 is released, and in position 13 a 105 circuit is closed from battery through the winding of relay 918, conductor 919, upper left and lower right contacts of cam 539, conductor 546, upper front contact of relay 916, lower front contacts of relay 836, to grounded conductor 441. Relay 918 extends the control conductors from the tens register 910 to the relays of office group register 1020 causing the operation of relays 1021, 1022 and 1024. It likewise advances sequence switch 110 500 to position 14.

In position 14, the fundamental circuit is the same as previously traced. The counting relay circuit extends as traced in position 12 to conductor 550, lower contact of cam 538, 115 conductor 547, front contact of relay 1021, inner front contact of relay 1022, to conductor 1081, back contact of the No. 3' relay 614, winding of the No. 3 relay 613, to battery. After the reception of three pulses, 120 the operation of relay 618 extends the counting relay circuit over the upper left contact of cam 519, front contact of relay 1024, conductor 1082, back contact of the No. 9' relay 602, winding of the No. 9 relay 601 to bat- 125 130

tery. The next five impulses operate relays 601 to 610 inclusive and the operation of relay 610 extends the circuit to the winding of relay 619. As before the operation of relays 5 621 and 622 in the locking circuit of relay 619 initiates the release of the counting relays, the advance of sequence switch 500 to position 15 and the advance of the final selector to position for making final units selection. 10 As sequence switch 500 leaves position 14, relay 918 is released and relay 928 operated over a similar circuit. Relay 928 advances sequence switch 500 to position 16, in which position the fundamental circuit is closed as 15 before. Since relay 921 was the only relay of register 920 which was operated, the operation of relay 928 does not cause the operation of any of the relays of register 1030. The counting relay circuit extends as previously 20 traced to conductor 550, over the upper contact of cam 542, conductor 524, over the back contacts of relays 1031, 1032 and 1033 to conductor 1084, upper right contact of cam 519, back contact of relay 1034, conductor 520 and 25 the winding of the No. 0 relay 619. The final selector is therefore operated to select the first line in the ninth group which bears the number 6780.

Following the selection of the called line, 30 sequence switch 500 is advanced to position 17. At this time the incoming selector is advanced to a position in which the connection of the battery and ground to the fundamental circuit is reversed. With sequence switch 500 35 in position 17, the fundamental circuit extends as previously traced with the exception that the battery is connected to conductor 555 instead of to conductor 418 as in the previous cases. Therefore, polarized relay 512 operates at this time. Relay 511 also operates. 40 Relay 512 closes a holding circuit for itself from battery through its left winding and the lower contacts of cam 549 to ground at the front contact of relay 512. It also closes a 45 circuit over the left contacts of cam 540, to the winding of relay 521. Relay 521, in operating, opens the usual operating circuit for relay 623. In conjunction with relay 511, it closes a circuit from battery on conductor 624, 50 through the winding of relay 619, conductor 520, outer right front contact of relay 521, upper contacts of cam 515, front contact of relay 511, to ground at the lower contact of cam 514. Relay 619 operates and closes the usual 55 locking circuit for itself which is ineffective to operate relays 620 and 621 as long as the fundamental circuit remains closed. However, the establishment of the fundamental circuit at this time causes the incoming selector to open it, permitting relay 511 to release 60 and relays 620 and 621 to be operated. Relay 621, in operating, closes a circuit from ground over its front contact, the middle right front contact of relay 521, to the winding of 65 relay 460, and battery. Relay 460 in operat-

ing closes a circuit from ground over the upper right contact of cam 448, left front contact of relay 460, to the winding of relay 408. Relay 408 operates and closes a circuit from battery through the winding of relay 623, 70 right front contact of relay 408, to ground at the upper right contact of cam 557. Relay 623 locks to the lower right contact of cam 518 and operates relay 622 as usual to release relays 619, 620 and 621. Relay 623 advances 75 sequence switch 500 to position 18 in the usual manner, releasing relays 512 and 521. Relay 460 locks over its middle left contact of grounded conductor 414, holding relay 408 operated. 80

With relay 408 operated, the shunt which has been closed at its left back contact around the right winding of relay 501 is opened and the resistance of this circuit is increased to such an extent that relay 329 of the district 85 selector releases. The release of relay 329, in turn releases relay 318, and permits the advance of sequence switch 300, to position 11. Sequence switch 300 is then immediately advanced to position 12 in a circuit from battery 90 through the magnet winding, lower right contact of cams 327 and 320, upper left contact of cam 320 to ground at the lower contact of cam 321. In position 11, ground is connected over the lower contact of cam 330 to conductor 328, 95 and thence to the winding of relay 501, so that relay 501 releases, in turn releasing relay 502. The release of relay 502 closes a circuit from battery through the winding of relay 407, inner right front contact of relay 413 to ground at 100 the inner left back contact of relay 502. Relay 407 operates, connecting ground to the circuit of relay 413, so that relay 413 releases. Relay 407 is held operated, however, over its outer right front contact and the ground connected to conductor 406 from the district selector. With sequence switch 500 in position 105 110 115 120 125 130 135 140 145 150 155 160 165 170 175 180 185 190 195 200 205 210 215 220 225 230 235 240 245 250 255 260 265 270 275 280 285 290 295 300 305 ping relay of the sender in a manner similar to the revertive impulses from the commutator. Since talking selection relay 1071 is operated, the counting relay circuit closed by 5 relay 511 extends as traced to conductor 554, over the outer right front contact of relay 460, right back contact of relay 551, conductor 552, front contact of relay 1071, back contact of relay 1072, to conductor 1080, back contact of the No. 11 relay 618, winding of the No. 1 relay 617, to battery. When sequence switch passes through 12 $\frac{3}{8}$, relay 618 operates in the locking circuit of relay 617 and extends the counting relay circuit over the 10 lower contact of cam 519, to the winding of relay 619. As sequence switch 300 passes through position 13 $\frac{3}{8}$, relays 620 and 621 operate in the locking circuit of relay 619. Relay 620 opens the circuit of relay 318 and that 15 relay releases bringing sequence switch 300 to rest in position 14. The operation of relay 621 closes a circuit from ground over its front contact, back contact of relay 521, lower contact of cam 522, winding of relay 423 to battery. Relay 423 closes a locking circuit for 20 itself over its inner right front contact to grounded conductor 414. It also closes a circuit from battery through the winding of relay 623, outer right front contact of relay 423, lower left contact of cam 553 to ground. Relay 623 operates relay 622, releasing the 25 counting relays and advancing sequence switch 500 to position 1 in the usual manner. The advance of the sequence switch releases 30 relays 622 and 623.

Relay 423 also closes a contact from battery through resistance 405, left front contact of relay 423, inner right front contact of relay 407 to conductor 406, causing the link circuit 35 to open all the conductors connecting the district selector with the sender. Relay 407 releases, operating relay 411 over the upper left contact of relay 410, back contact of relay 413, inner back contact of relay 410 to ground, in 40 turn advancing sequence switch 400 to normal from any off-normal position on which it may be. The return of both sequence switches 400 and 500 to position 1 opens all the off-normal ground leads and releases all relays which 45 may be locked up at the time.

If the sender fails to release correctly, a circuit is closed, as soon as relay 318 releases with the district selector in positions 13 to 15 and also as it passes through position 17 from 50 ground over the upper right contact of cam 306 right back contact of relay 318, lower right and upper left contacts of cam 339, to conductor 308 through the link circuit to conductor 419, outer left back contact of relay 502, upper right and lower left contacts of cam 522, winding of relay 423 to battery, to attempt to bring about the release of the 55 sender.

With sequence switch 300 in position 14 60 the calling subscriber's talking circuit ex-

tends from battery over the lower left winding of repeating coil 355, upper contact of cam 366, winding of supervisory relay 358, lower back contact of relay 324, through the line finder, over the subscriber's substation 70 loop, back to the line finder, upper back contact of relay 324, lower contact of cam 335, upper left winding of repeating coil 355 to ground. The called subscriber's talking circuit receives current from the incoming selector 380 and a circuit is also closed from the incoming selector 380 through the office selector 370, district selector brush 350, over the upper contacts of cam 351, upper right winding of repeating coil 355, left contacts 75 of cam 356, through the winding of polarized relay 357, lower right winding of repeating coil 355, lower contacts of cam 353, brush 354, through the office selector 370 back to the incoming selector 380. When the called subscriber answers, the current flow in this circuit is reversed so as to operate relay 357. Relay 357 in operating closes a circuit from ground over the lower right contact of cam 306, front contact of relay 357, left contacts of cam 342, to interrupter 359. When the interrupter closes its upper contact, the circuit is extended to the winding of relay 305 which relay operates and locks over its inner left front contact, lower left contact 80 of cam 342 and the front contact of relay 357 to ground. When interrupter 359 closes its lower contact, the circuit is extended from ground as previously traced over the lower contact of interrupter 359, right front contact of relay 305, upper contact of relay 310 to battery through winding of relay 352. Relay 352 locks over its middle left front contact to ground at the upper right contact 85 of cam 306. When the calling subscriber hangs up his receiver, relay 358 releases, closing a circuit from battery through the winding of relay 329, back contact of relay 358, upper contact of interrupter 360, left contacts of cam 345 to ground. Relay 329 locks over the back contact of relay 358, left contacts of cam 347, left front contact of relay 329, commutator strip 348, brush 349 to ground. Relay 329 also closes a circuit from 90 battery through the lower winding of relay 324, right front contact of relay 329, lower contact of interrupter 360, to ground at the left contacts of cam 345. Relay 324 locks over its upper front contacts, upper left contact of cam 306 to ground. Relay 324 opens the tip, ring and sleeve conductors from the calling subscriber's line freeing it for other calls. It also closes a circuit from battery through the winding of sequence switch magnet 300, lower contacts of cam 304, upper contacts of relay 324 to ground at the upper left contact of cam 306. Sequence switch 300 advances to position 17 in this circuit. As sequence switch 300 passes from position 15 to 16 relays 305, 357, and 329 release. In 100 105 110 115 120 125 130

- positions 15+17, the operated condition of relay 352 connects battery through resistance 361 over the inner front contact of relay 352, upper contacts of cam 362, to terminal 319 to 5 operate the message register (not shown) associated with the subscriber's line. In position 17, relay 329 again operates under the control of interrupter 360 and locks. Relay 305 is also reoperated in a circuit over the 10 lower right and lower left contacts of cam 368, front contacts of relay 324 to ground at the upper left contact of cam 306. Relay 305 locks over its left front contact, lower right contact of cam 311, commutator strip 15 348, brush 349 to ground. Relay 352 also connects battery through resistance 322, lower left contact of cam 323, outer left front contact of relay 352, resistance 325, to terminal 326 to hold the line busy. This battery 20 is removed when sequence switch 300 leaves position 17½, at which time relay 352 releases. Relay 305 advances sequence switch 300 to position 18 over a circuit including the lower left contact of cam 307, right front 25 contact of relay 305, to ground at the lower left contact of cam 306, releasing relay 329.
- In position 18, district selector down-drive magnet 363 is operated over the upper right and lower left contacts of cam 317, right back 30 contact of relay 318, lower right and upper left contacts of cam 345 to ground. Line finder down drive magnet 369 is also operated over the lower right contact of cam 310, right front contact of relay 305 to ground at the 35 lower left contact of relay 306. When the line finder reaches normal, relay 305 is released. When the district selector reaches normal, a circuit is closed from battery through the winding of sequence switch magnet 300, upper right contact of cam 327, normal commutator segment 364, brush 340, lower contact of cam 321 to ground. The 40 circuit of downdrive magnet 369 is maintained in position 1 to insure its complete 45 restoration should the district selector reach normal before the line finder. The operation of the district selector in being selected by a link circuit, is the same as described in the above identified patent to O. H. Kopp, No. 50 1,589,402.
- Call to manual offices.*
- If the called line had been located in an office which could be reached from the office shown only through a tandem office, the contacts of the trunk group relay such as relay 1800 would be cross connected to operate relay 1503 through its right winding. Relay 1503 in turn causes the operation of relay 55 508. The remaining registers will be set to select the proper group of outgoing trunks. The operation of the district selector and office selector will be the same as described for a call to a full mechanical office.
- 60 When sequence office 500 arrives in position 7 following office brush selection, the trunk test circuit is closed as described for the former call except that relay 503 being deenergized, it extends over the inner right back contact of that relay, right contacts of cam 528, winding of relay 529, back contact of relay 620, outer back contact of relay 623, right winding of relay 512, left contacts of cam 531, through resistance as determined by the setting of the compensating resistance 70 register 1010, left contact of cam 532 to conductor 555. Relay 529 operates, in turn operating relays 533 and 534. Relay 534 locks over its inner left front contact, upper right contact of cam 553 to ground to prevent its 75 release should the manual operator respond before sequence switch 500 leaves position 7. It also closes a circuit from ground at its right front contact, lower left contact of cam 535, outer right back contact of relay 503, outer right front contact of relay 508, left back contact of relay 551, winding of relay 509 to battery. Relay 509 locks over the left back contact of relay 551, middle left contact of relay 509 to grounded conductor 414. 80 It also closes a circuit from ground at its outer right front contact, lower right contact of cam 523 to the winding of magnet 500, advancing the sequence switch to position 17. The establishment of the fundamental circuit informs an operator at the called office 85 that a call is waiting. The depression of the assignment key removes battery and ground from the fundamental circuit and extends it to the polarized and marginal relays of the call indicator. For a complete description of the operations at a manual office reference may be made, to U. S. Patent 1,464,084, granted to A. E. Lundell et al., August 7, 1923. In a mechanical tandem office these 90 operations take place automatically. Such an office is disclosed in Patent No. 1,613,613, issued to O. H. Kopp, January 11, 1927.
- The operation of the assignment key releases relay 529 in turn releasing relay 533 100 and relay 534 if sequence switch 500 has left position 7. With relay 534 released, relay 509 operated and class relay 508 operated, conductor 418 is extended over the inner left front contact of relay 509, left back contact of relay 534 to conductor 558 and the impulser switch indicated by a rectangle in Fig. 7. Likewise conductor 555 is extended over the left contact of cam 532, through the compensating resistance register 1010, inner 105 left front contact of relay 509, outer left back contact of relay 534 to conductor 559 and the impulser switch. The impulser switch is started when relay 534 releases closing its inner right back contact and sends out impulses in substantially the manner described in the above mentioned patent to Lundell et al., the nature of the pulses being controlled by the upper armatures of the recording register relays. At the completion 110
- 115
- 120
- 125
- 130
- 135

of the revolutions of the impulser switch relay 460 is operated from that switch, initiating talking selection and the release of the sender which take place as described in connection with a mechanical call.

5 Where the called party is located in a directly reached manual office relay 1504 is operated by the trunk group relay, in turn operating relay 1502 and these relays operate class relays 507 and 508 together. Impulses are sent corresponding only to the numerical designation. Otherwise the operation is substantially the same as for the tandem operation.

15 *Calls to operators.*

When the subscriber fails to dial or dials an operator's code, the call will be routed to an A operator's position for the purpose of aiding the subscriber in obtaining a connection. If the subscriber fails to dial, the operation of relay 453 selects the proper trunk group relay. If he dials a three-digit operator's code, the trunk group relay is selected in accordance with the setting of the registers. If he dials zero the operation of the zero relay 721 of register 720 causes the operation of relay 431 to associate a decoder with the sender. When relay 427 releases, a circuit may be traced from grounded conductor 414 over the lower front contacts of relay 726, back contact of relay 725, through the decoder connector to the windings of decoder relays 1305 and 1307. A circuit is also extended from ground at the inner left front contact of relay 426, back contact of relay 427, conductor 429, back contacts of relays 937, 927, 917, 837 and 827, through the winding of relay 816, back contact of relay 815, through the decoder connector to the windings of relays 1325 and 1327. A branch of this last circuit extends over the back contact of relay 817, winding of relay 836, back contact of relay 835, through the decoder connector to the windings of relays 1315 and 1317. Three digits zero are therefore registered in the decoder so that relay 1330 may be operated to supply ground to register 1300 for operating the proper trunk group relay. In this case relay 1502 is operated, in turn operating relay 507. The district, or district and office selections take place as above described. In position 7 the trunk test circuit is the same as for a relay call indicator call. Relays 529, 533 and 534 are operated by this circuit. The operation of relay 534 completes a circuit from battery through the winding of relay 560, outer right back contact of relays 508 and 503, lower left contact of cam 535, to ground at the right front contact of relay 534. Relay 560 locks to grounded conductor 414. Relay 560 advances sequence switch 500 to position 10 in a circuit extending from battery through the magnet winding, upper left contact of

cam 536, inner left contacts of relay 560 to grounded conductor 414. As the switch passes through position 9 1/4 a circuit is closed from grounded conductor 414, over the outer front contact of relay 560, lower contact of cam 561, winding of relay 460 to battery. Relay 460 operated advances sequence switch 500 to position 17 in a circuit extending from the magnet over the upper right contact of cam 536, innermost left contact of relay 460 to grounded conductor 414. When switch 400 has been advanced to position 12, relay 408 is operated over the outer left front contact of relay 460 to ground at the upper left contact of cam 448. This delay is made to prevent interference with the district which would occur if the talking conductors were closed before the subscriber ceased dialing. With relay 408 operated and sequence switch 500 in position 17, a circuit is closed from battery through the winding of relay 623, right front contact of relay 408, upper right contact of cam 557 to ground. Relay 623 advances sequence switch 500 to position 18. The operation of the sender in connection with talking selection and release is the same as described, except that a different combination of relays is operated in register 1070 and the district selector occupies a different talking position. The operation of the district selector in the case of a call to an operator is disclosed in U. S. Patent 1,589,402 to O. H. Kopp, granted June 22, 1926.

In manual offices either stations designations or five place numbers lying between 10,000 and 10,499 or both may be used, but in the last case, no stations letter is given to numbers between 1050 and 1099. Relay 1051 is operated when stations letters are used, relay 1052 is operated when five place numbers are used and both relays are operated when both are used at the called office. Therefore when relay 1051 is operated alone or with relay 1052, the advance of sequence switch 400 to position 12 is delayed until relay 936 operates following the registration of the stations letter, or is made under the control of interrupter 449. Where five place numbers are used it is only necessary to delay the advance of switch 400 if the first two digits dialed are 1 and 0, respectively. Therefore the circuit of relay 1053 extends over conductor 1054, back contacts of relays 825, 823, 821, front contact of relay 831, back contact of relay 824, lower front contacts of relay 826 to grounded conductor 430. With relay 1053 operated alone, the advance is not delayed, but with relay 1052 also operated the advance awaits the operation of relay 936. Even in this case, since stations digits are never suffixed to numbers between 1050 and 1099, the registration of any of which would cause the operation of relay 915, a circuit is closed for advancing switch 400 without delay which extends as previously traced to con-

ductor 443, over the front contact of relay 915, conductor 940, front contact of relay 1052, front contact of relay 1053 to ground.

- All points on the multi-contact relays of 5 Fig. 17, which correspond to unassigned codes or those to which the service is restricted are routed to a different set of operators from those above mentioned. No class relay is operated in this case. Such an office code 10 will probably be followed by a number, hence the establishment of the trunk test circuit, which serves to signal the operator, is delayed until the number has been completely dialed. To this end relay 623 is held operated in position 15 6 until sequence switch 400 has reached position 12 in the manner above described. This holding circuit extends from battery through the winding and inner left front contact of relay 623, upper contact of cam 518, lower 20 contacts of cam 461, left back contact of relay 503 to ground at the outer back contact of relay 507. When switch 400 reaches position 12, relay 623 is released and the trunk test circuit established. Otherwise, the operation 25 is the same as described for a call intended for an operator.

Where part of the subscribers are restricted from calling certain offices, these subscribers are served by a particular group of 30 link circuits, district selectors and senders. These senders supply ground over grid wire 1221 to conductor 1222, winding of relay 1336 and battery. With relay 1336 operated, when registers 1300, 1310 and 1320 have been 35 set and relay 1330 operates, relay 1335 is operated over the front contact of relay 1336. The trunk group relay corresponding to a restricted code will be connected in series with a restricted code relay, for example relays 40 1802 and 1805. When these relays operate, a circuit is closed from ground over the outer right front contact of relay 1335, conductor 1337, cross-connecting racks 1826 and 1806, inner right front contact of relay 1805 to the 45 winding of relay 1801 and battery. Relay 1801 operates the selection controlling registers to route the call to an operator's position where it can be recorded. If the subscriber is entitled to free service, no ground is supplied to operate relay 1336 and relay 1334 is 50 operated over back contact of relay 1336. A contact of relay 1334 will be cross-connected over the left front contact of relay 1805 to the windings of relays 1803 and 1804 in parallel. These relays supply ground to the 55 armatures of relay 1802 which are cross-connected to establish a registration for extending the connection to the wanted office.

Additional decoder functions.

60 It will be remembered that the relays of the outgoing decoder registers may be operated through either of two windings. When energized through their left windings the 65 energizing ground is extended over the left

contact to control particular functions. In the case of register 1500, the energization of a relay through its left winding grounds conductor 1507 to cancel the coin test on calls to an operator, etc. This conductor therefore is 70 only effective in the case of lines equipped with coin boxes. In the case of register 1510 the energization of a relay through its left winding grounds conductor 1524 to operate talking selection relay 1072 which, together 75 with relay 1071, causes the district selector to advance to position for talking with an operator. The relays of register 1530 when energized through their left windings ground conductor 1542 to operate relay 1052. This 80 relay indicates an office employing five digit numbers. The 5 digit numbers employed, lie between 10,000 and 10,499. Therefore, when register 820 is set for the digit 1, and register 830 is set for 0, a circuit is closed from 85 battery through the winding of relay 1053, conductor 1054, back contacts of relays 825, 823 and 821, front contact of relay 831, back contact of relay 824, lower front contact of relay 826 to grounded conductor 818. With 90 both relays 1052 and 1053 operated, the circuit for advancing timing switch 400 is not completed until the stations register 930 has been set, since the circuit then extends from battery through the left winding of relay 95 411, lower right contact of cam 410, conductor 443, to ground at the upper front contact of relay 936, the circuit over the back contact of relay 1051 being open at the contact of relays 1052 and 1053. A circuit is 100 also closed from ground over the front contacts of relays 1053 and 1052, conductor 940, lower back contact of relay 915, middle front contact of relay 936, and conductor 738 to a relay in the impulser circuit (not shown) 105 which varies the order in which the digits are transmitted to the manual office.

When a relay of register 1400 is operated through its left winding it grounds conductor 1414 which is extended to a relay (not shown) 110 which alters the operation when extending a call to what are known as two wire office selectors. The relays of register 1420 ground conductor 1428 when energized by their left windings in order to operate relay 1025. 115 This relay is known as the "skip-office" relay and is employed when the outgoing trunk group appears on the district selector so that no office selections need be made.

Relay 1025 when operated closes a circuit 120 from ground at its right contact, lower right contact of cam 518, middle front contact and winding of relay 623 to battery, holding relay 623 operated in positions 2 to 6 inclusive to advance sequence switch 500 directly from district group selections to trunk test position 7.

The relays of register 1440 when operated over their left windings ground conductor 1457 to operate relay 1015. Relay 1015 is 130

operated when the trunks of the group are short and removes the shunt from resistance 556 to equalize the trunk resistance so that the marginal operation of relay 529 may be 5 improved.

Decoder connector.

Figs. 1 and 2 have been included for the purpose of more clearly showing the relationships between the senders and decoders. 10 The senders are divided into groups, each group being served by a separate section or channel of the decoder connector. The circuits are so arranged that only one sender can 15 be served by a channel at one time.

If a plurality of senders such as senders 1 and 2 in the same channel, such as channel 1, require the services of a decoder at the same time, they may operate their decoder start 20 relays 201 and 202 simultaneously but the locking of the relay nearest the common relay 203 in the chain, in this case relay 201, releases the remaining start relays. When the common relay is released, the next nearest 25 sender receives its turn, and so on.

All the decoders appear in each channel, and are arranged to be used in a predetermined order. Assuming that there are six 30 decoders, each decoder will be the first choice in one-sixth of the channels. When a decoder is taken for use a relay, such as relay 204, common to all channels is operated, causing the decoder to be marked busy to each channel and the extension of the start circuit to the 35 decoder appearing as the next choice, which need not be the same decoder in each case. If sender No. 1 demands a decoder when all 40 are busy as indicated by the operation of relays 205, 206, 207, 204, 210 and 211, relay 203 will remain operated holding battery to conductor 208. Assuming that decoder No. 2 is the first to be freed, relays 209 and 210 45 will release and the start circuit will be extended over the upper front contact of relay 208, upper back contact of relay 209 to ground at the back contact of relay 210.

Sender No. 1 in both the first channel and the last channel of two senders in different channels, for example desire decoders simultaneously when all decoders are busy and decoder No. 2 is the first one free, relay 210 will be released, in turn, releasing relays 209 and 109. The start circuit from the front contact of relay 103 extends over the back contacts of the multi-contact relays of the last channel, back contact of relay 106 to the upper winding of relay 109 and ground at the back contact of relay 210. The start circuit from the front contact of relay 203 of the first channel extends over the back contacts of the multi-contact relays, front contact of relay 205, back contact of relay 206 to the upper winding of relay 209 and ground at the back contact of relay 210. Relays 109 65 and 209 operate and attempt to close locking

circuits. Decoder No. 2 is the first choice decoder for the last channel as indicated by the connection of relay 210 to the lower armature of relay 109. Therefore, relay 109, in operating, closes a circuit from battery, 70 through its lower winding and lower front contact to the winding of relay 210 and ground. Relay 210 operates and removes ground from the energizing circuit of relay 209. The locking circuit of relay 209 extends over the back 75 contact of relay 109 and hence cannot be completed. Decoder No. 3 will be the first choice for some other channel and relay 211 is shown terminating in the dotted lines which represent other channels. It is therefore apparent 80 that if a number of senders in different channels wish a decoder simultaneously and all decoders are busy, the first decoder freed will be associated with the sender in the channel for which that decoder is first choice or ear- 85 liest choice. The release of the decoder connector being controlled by the sender a group of lamps are provided to identify the sender if the connector is not released. As each sender multi-contact relay is operated it starts 90 a timed alarm. If it fails to release in a given length of time an alarm is sounded. A key may then be operated to supply battery to the group of lamps. Two lamps will then be lighted, over contacts of the operated 95 multi-contact relay one individual to the channel and one individual to the position of the sender in the channel. If a decoder fails to complete its operation and to connect ground to conductor 1333 within a period of 100 time measured by the decoder timing device, ground will be connected from the timing device to conductor 1524 which will be ex- 105 tended to conductor 1224 over the right back contact of relay 433 to the winding of relay 434 and battery. Relay 434 operates opening the start circuit to the decoder connector and releases the decoder. Relay 434, in oper- 110 ating, also closes a locking circuit for itself through the left winding of relay 433, left front contact of relay 434 to grounded con- 115 ductor 414, which circuit is ineffective as long as ground is connected to conductor 1224. When the decoder has been disconnected and ground removed from conductor 1224, relay 433 120 operates closing a direct locking circuit for itself from battery through its right winding and inner right front contact to grounded conductor 414. With relays 433 and 434 both operated, battery is again con- 125 nected to the start circuit and connection with another decoder is made. Should this de- 130 coder fail to release ground will again be connected to conductor 1224 which extends over the outer right front contact of relay 433 to the battery which operated relay 434 shunting that relay and again opening the start circuit of the decoder connector. Re- 130 lay 433, however, remains operated and an operator is signaled when sequence switch

400 reaches position 7 or 18, whichever occurs next.

What is claimed is:

1. In a telephone exchange system, a plurality of senders, means in each sender for recording dial impulses, a group of decoders common to said senders, means in each sender to cause the association of an idle decoder therewith, a switch controlling register in each sender, means in said decoder to designate a setting for said switch controlling registers, and means to set said registers in accordance with said designation.
2. In a telephone exchange system, a plurality of senders, means in each sender for recording dial impulses, a group of decoders common to said senders, means in each sender to cause the association of an idle decoder therewith, a switch controlling register in each sender, means in said decoder to designate a setting for said switch controlling registers, means to set said registers in accordance with said designation, and means in each sender actuated by associated register setting means to dismiss said decoder.
3. The combination in a telephone system of selector switches, means for extending connections to said switches, a number of senders having registers for recording dial impulses and registers for controlling said selector switches, a number of decoders commonly available to said senders, means for connecting a sender with any one of said decoders, cooperating means in the sender and decoder responsive to such connection for operating the decoder for deciphering impulses recorded in the sender, and means in the decoder responsive to said operation for setting the switch controlling registers in the sender.
4. The combination in a telephone system of selector switches, means for extending connections to said switches, a number of senders having registers for recording dial impulses and registers for controlling said selector switches, a number of decoders commonly available to said senders, means for connecting a sender with any of said decoders, cooperating means in the sender and decoder responsive to such connection for operating the decoder for deciphering impulses recorded in the sender, means in the decoder responsive to said operation for setting the switch controlling registers in the sender, and means actuated in accordance with the setting of said registers to control the operation of said selector switches in accordance with said recorded impulses.
5. The combination in a telephone system of selector switches, means for extending connections to said switches, a number of senders having registers for recording dial impulses and registers for controlling said selector switches, a number of decoders commonly available to said senders having mechanism for deciphering recorded impulses and mech-

anism for setting switch controlling registers interconnected by a plurality of terminal contacts, means to connect a sender with a decoder, cooperating means in the sender and decoder for operating the decoder so connected for deciphering impulses recorded in the sender, and means in said decoder responsive to said operation for marking a single one of said terminals to designate the setting for the switch controlling register of said sender.

6. The combination in a telephone system of selector switches, means for extending connections to said switches, a number of senders having registers for recording dial impulses and registers for controlling said selector switches, a number of decoders each comprising a plurality of relays, said decoders being commonly available to said senders, means to connect a sender with any one of said decoders, cooperating means in the sender and decoder responsive to such connection for operating the decoder for deciphering impulses recorded in the sender, and means in said decoder responsive to said operation for operating a single one of said relays to designate a setting for the switch controlling register of said sender.

7. The combination in a telephone system of selector switches, means for extending connections to said switches, a number of senders having registers for recording dial impulses and multi-relay registers for controlling said selector switches, a number of decoders commonly available to said senders, means to connect a sender with any one of said decoders, cooperating means in the sender and decoder responsive to such connection for operating the decoder for deciphering impulses recorded in the sender, and means in the decoder responsive to said operation for simultaneously operating all of the relays of the sender switch controlling register to be set for the control of said switches in accordance with said deciphered impulses.

8. The combination in a telephone system of selector switches, means for extending connections to said switches, a number of senders having registers for recording dial impulses and registers for controlling said selector switches, a number of decoders commonly available to said senders, a plurality of relays in said decoder, means to connect a sender with any one of said decoders, cooperating means in the sender and decoder responsive to such connection for operating the decoder for deciphering impulses recorded in the sender, means responsive to the operation of said deciphering means to select and operate one of said relays, and means under the control of said relay for simultaneously operating the relays of the switch controlling register for complete control of said switches.

9. The combination in a telephone system of selector switches, means for extending con-

nections to said switches, a number of senders having registers for recording dial impulses and registers for controlling said selector switches, a number of decoders commonly available to said senders, means to connect a plurality of senders indiscriminately with an equal plurality of said decoders, and cooperating means in the senders and decoders responsive to such connections for operating the decoders for deciphering the impulses recorded in the respective senders and for setting the switch controlling registers in said senders in accordance with said deciphered impulses.

15 10. The combination in a telephone system of selector switches, means for extending connections to said switches, a number of senders having registers for recording dial impulses and registers for controlling said selector switches, a number of decoders commonly available to said senders, means to connect a plurality of senders indiscriminately with an equal plurality of said decoders, and means in said decoders operated in response to said connections for simultaneously deciphering the impulses recorded in the respective senders and for setting the switch controlling registers in said senders in accordance with said deciphered impulses.

30 11. The combination in a telephone system of selector switches, means for extending connections to said switches, a number of senders having registers for recording dial impulses and registers for controlling said selector switches, a number of equivalent control mechanisms comprising a plurality of relays, means to connect a plurality of senders indiscriminately with an equal plurality of said controlling mechanisms, and means in said controlling mechanisms operated in response to said connections for simultaneously deciphering the impulses recorded in the respective senders and for operating a single relay in each mechanism for designating the 45 setting of the switch controlling registers in respective senders.

12. The combination in a telephone system of selector switches, means for extending connections to said switches, a number of recording mechanisms commonly available to said switches arranged for recording series of impulses and for controlling the movement of said switches in accordance with deciphered records of said recorded impulses, a number 50 of equivalent controlling mechanisms commonly available to said recording mechanisms, means for connecting a plurality of said recording mechanisms indiscriminately with an equal number of said controlling mechanisms, means to operate said controlling mechanisms for simultaneously deciphering impulses recorded and for setting up

switch controlling records in the recording mechanisms connected therewith.

13. In a telephone exchange system, a sender, a primary register in said sender for recording dial impulses, selective switches, a secondary register in said sender for controlling said selective switches, and means to repeatedly control said secondary register for 65 different settings in accordance with a single recording of dial impulses upon said primary register.

14. In a telephone system, subscribers' lines of a plurality of classes, a sender associable with said lines comprising a register for recording dial impulses, and a register for controlling selections, a decoder, means for associating said decoder with said sender, means in said decoder to designate a setting for said 75 switch controlling register in accordance with the setting of said recording register, and means effective in response to certain settings of said recording register to discriminate between a plurality of settings of said selection controlling register in accordance with the class of the calling subscriber.

15. In a telephone system, subscribers' lines of a plurality of classes, a sender associable with said lines comprising a register 90 for recording dial impulses, and a register for controlling selections, a decoder, means for associating said decoder with said sender, means in said decoder to designate a setting for said switch controlling register in accordance with the setting of said recording register, and means in said decoder effective 95 in response to certain settings of said recording register when the calling subscriber's line is of a particular class to render said designation ineffective and to designate a different setting for said selection controlling register.

16. In a telephone system, subscribers' lines of different classes appearing in one office, other office calls to which are restricted in the case of certain classes of subscribers, a sender associable with a subscriber's line comprising a register for recording dial impulses and a register for controlling selections, a decoder, means for associating said decoder with said sender, means in said decoder to designate a setting for said selection controlling register whereby a calling line may be extended to the office whose designation has been recorded on said recording register, and means operated when the call is initiated by a 105 subscriber's line of a restricted class to render said designation ineffective and to designate a setting for said selection controlling register whereby said line may be extended to an 110 operator's position.

In witness whereof, I hereunto subscribe my name this 3 day of December, A. D. 1926.

FRANKLIN A. STEARN.
